ADDING AND SUBTRACTING MACHINE.

Application filed April 1, 1924. Serial No. 703,474.

The present invention relates to computing machines which are arranged to perform addition and subtraction, and in connection with such machines the invention relates more particularly to improvements in the construction and operation of the carry tension mechanism.

Some of the objects of the present invention are to provide a computing machine in which either steps of addition or subtraction can be performed, either being thrown into operation at will to change from one method of calculation to the other; to provide an improved carry tension mechanism for computing machines; to provide a carry tension mechanism which is positive and sure in operation and in the use of which it is impossible for any carry rack to carry over more than one number unit; to provide a carry tension mechanism having a spring tension which is practically negligible in effect upon the main operating lever of the machine; to provide a carry tension mechanism having a substantially uniform spring tension; to provide a simple and effective means for setting the carry racks to respond to the action of the carry tension mechanism at the proper time in the cycle of operation; to provide a simple and efficient means for changing the operation of the machine from an adding function to a subtracting function, or vice versa, as required; to provide an automatic means for changing the direction of the applied force upon the carry tension mechanism when a change is made from an adding function to a subtracting function, or vice versa; and to provide other improvements as will hereinafter appear.

In the accompanying drawings, Fig. 1 represents an elevation of one side of a computing machine showing the mechanism embodying one form of the present invention for causing actuation of the carry tension mechanism; Fig. 2 represents an elevation of the opposite side of the machine showing those parts having relation to the operation of the carry tension mechanism; Fig. 3 represents a detail in plan of one of the carry racks and the numeral wheel operating adjuncts; Fig. 4 represents a detail in side elevation of one form of carry rack control mechanism; Fig. 5 represents a detail in side elevation of one of the carry tension

units embodying one form of the present invention; Fig. 6 represents an edge elevation of the same.

Referring to the drawings, one form of the present invention is illustrated as applied to an adding and subtracting machine of the type operated by rotatable number or accumulator wheels 10, which are arranged to be actuated by pinions 11 through engagement with index racks 12 at certain predetermined times. It will be understood, by reference to Fig. 3, that in the present instance one unit only of the machine is described, but in practice there may be any number of these units with the accumulator wheels arranged side by side, each having numbers from naught to nine, so that the sequence of operation is by way of the nine members of the unit wheel, then a carry of one to the ten wheel, and so on with a succession of carry numbers from one wheel to the other throughout the succession, depending upon how many accumulator wheels there are in a machine. It will be understood that in this type of machine there is one index rack 12 for each pinion, and that the racks are operated through the medium of a main operating machine arm 13, which in the present instance connects through a link 14 to a main cam 15 on the main shaft 16, and from which motion is transmitted to the index racks to cause their actuation in accordance with the respective set positions of these racks, as determined by the setting of the keys of the keyboard of the machine. This construction forms no part, however, of the present invention, and it is therefore believed unnecessary to describe it specifically, as obviously the present invention only requires the index racks to be actuated at the proper time and in the proper manner for the carrying out of the functions to which this invention relates.

In the type of machine here illustrative of the invention, the accumulator wheels 10 and pinions 11 are independently mounted for rotation upon a common pinion shaft 17, 100 the ends of which project through opposite side plates 18 of the main frame, and terminate in cam rollers 20, which are respectively located in the path of movement of side face cams 21 formed respectively upon reciprocable cam slides 22 and 23, which are mount-

ed for free sliding movement relative to the plates 18. In the present instance, each of these slides 22 and 23 is provided with three of the cams 21, spaced a like distance apart for the purpose of simultaneously acting in pairs upon the pinion shaft designed to be controlled thereby. This provision of additional cams is made to take care of additional pinion shafts, each of which is provided with a set of pinions and accumulator wheels, as will be understood, so that the machine can be equipped with one or more sets of adding and subtracting units. In normal or rest position of the machine, the cam slides 22 and 23 are in such a position that the cams 21 are directly beneath the rollers 20, and thereby hold the pinion shaft 17 in a position with the pinions 11 out of engagement with the index racks 12. In this connection, it will be understood that suitable spring mechanism is provided for holding the pinion shaft 17 in firm contact with the cam face of the slides 22 and 23. The function, therefore, of the cam slides 22 and 23 and cams 21 is first to maintain the accumulator pinions 11 normally out of engagement with the index racks 12 while determining in the operation of the machine the time of shifting of the pinions into mesh with the index racks 12 to roll an adding or a subtracting operation, as the case may be.

For the purpose of reciprocating the cam slides 22 and 23 at each adding or each subtracting stroke of the main operating arm 13, the cam slide 22 is provided at one end with a recess 24, which seats about a pin 25 on an arm 26, fast to a rock shaft 27, this last extending transversely of the machine to receive on its other end a second arm 28 carrying a pin 30, which seats in a recess 31 correspondingly located in the cam slide 23. Thus, movement imparted to the slide 22 will be translated to the slide 23 and the two operate in unison. To actuate the slide 22 it is provided at one end with a trip lug 32 pivoted on a pin 33, fast to the slide 22, the said pin 33 being intermediate the tripping end of the lug 32 and a stop pin 34, which in operating position of the lug 32 is arranged to abut the edge of a shoulder 35 formed on the slide 22. The opposite end of the slide 22 carries a similar trip lug 36, pivoted on a pin 37 on the slide 22 and also having a stop pin 38, to abut, in operating position of the lug, against the side face of a shoulder 40 on the cam slide. In this instance, the two lugs 32 and 36 are arranged to be projected into operating position by means of a common spring 41, which has its ends connected respectively to the aforesaid lugs at a point to carry out the desired operation. Where the machine is set to carry out adding operations, one of these trip

lugs will operate to shift the slides 22 and 23 from central position in the correct direction to cause an adding function, and when the machine is set for subtraction, the other of the lugs will be operated to cause the slides 22 and 23 to move from central position in the correct direction to carry out a subtracting function. In this instance, the lug 32 functions for the adding operation and the lug 36 for the subtracting operation, and selection of one lug or the other is made automatically, as will be explained. The mechanism which cooperates with the trip lugs 32 and 36 consists, in the present instance, of two trip pins 42 and 43, both fast to the face of the main cam 15, and so spaced apart and positioned as to come into the paths respectively of the two trip lugs 32 and 36 at the proper time and in accordance with the operation to be carried out. Thus, if the adding trip lug 32 is set so that it is in the path of the trip pin 42, the cam slides will be shifted to the right, whereas if the trip lug 36 is selected so that it is in the path of the trip pin 43, it will be operated, and the cam slides 22 and 23 moved to the left, as seen in Fig. 2.

It will be understood that suitable restoring mechanism is provided for returning the slides 22 and 23 to normal position after each operation; but as this mechanism forms a separate invention, it is believed unnecessary to illustrate or describe these particular details.

For the purpose of making the selection above referred to, namely, of positioning the correct trip lug corresponding to the operation which is to be carried out in the machine, a rock bar 44 is provided, which is suitably pivoted at 45 to a fixed part, and is so arranged and located that rocking movement in a clockwise direction, as shown in Fig. 2, will cause one end of the bar 44 to contact with the stop pin 34, and by movement in a counter-clockwise direction will cause its other end to engage the stop pin 38, and whenever either end of the bar 44 picks up one of the stop pins it causes the trip lug of that stop pin to be shifted about its center to thereby remove its tripping end from the path of the corresponding trip pin on the cam 15, so that when the latter is rocked during an operation of the machine, it will fail to engage that particular trip lug. For convenience, the rock bar 44 will be considered as a subtraction lever 46 at one end and an addition lever 47 at the opposite end. The position of the rock bar 44 is determined by an index arm 48 secured thereto and extending to a convenient location adjacent the position of the operator of the machine, so that it can be quickly changed from one position to the other. This index arm 48 is provided with a later-

- ally disposed locking pin 50, which is arranged to be engaged by a pivoted latch 51 normally held in engagement with the pin by means of a spring 52, and having three recesses 53, 54 and 55, one, 53, of which serves to lock the index arm in adding position, another, 55, in subtracting position, and the intermediate one, 54, in total position.
- 10 In order to carry over an addition or a subtraction from one accumulator wheel to the next succeeding wheel, carry racks 56 are employed, each being operatively located with respect to the wheel pinion which 15 it is to control. These carry racks 56 are supported and slidably guided by transversely disposed guide strips 57, while across the path of movement of the respective ends of the carry racks 56 are two movable 20 setting bars 58 which are arranged to be automatically operated in proper timed relation to not only reset the carry racks 56 after a carry operation but also to move out of the path of the aforesaid carry racks 25 56 to allow them to function. For the sake of clearness but one carry rack 56 with its parts comprising one unit will be here described in detail, as the several units are of duplicate construction. The carry rack 30 56 is provided on the edge toward the numeral pinion 11 with three rack teeth 60 which are located to mesh with the pinion 11 under normal conditions, and thus serve as a lock to prevent improper movement of 35 the wheel 10 while also providing for the necessary carry movement to the adjacent wheel at the desired time, in either direction.
- As a means for locking the carry rack 56 in its normal position, it is provided with a slot 61 opening into a locking notch 62 to receive a tab or detent 63 of a latch 64 and provide a snug seating fit so that when the detent 63 is in the notch 62 the 40 carry rack 56 is locked against movement in both directions. The length of the slot 61 is such that when the latch detent 63 is withdrawn from the notch 62 the stroke or carry movement of the rack is limited to a 45 distance sufficient only to move the pinion 11 one tooth on its pitch line, and this is true whether the rack 56 is shifted to carry an adding or a subtracting transfer.
- For actuating the latch 64 so that the 50 carry rack 56 is set for operation it is pivoted at 65 to a fixed strip 66 and is normally held by a spring 67 under tension to return and maintain the locking detent 63 seated in the notch 62. The latch 64 is provided 55 with a trip finger 68 projecting into the path of a trip 70 carried by the hub or pinion of the next preceding accumulator wheel 10 and located thereon at the proper point to transfer the addition or subtraction from one 60 wheel to the next. This trip 70 has an en-
- gaging face 71 on one side to actuate the latch 64 in one direction for addition carry, and another engaging face 72 on the opposite side to actuate the latch 64 in the opposite direction for subtraction carry.
- The carry tension mechanism, whereby the carry rack 56 is operated or fired when released by the latch 64, consists of a bell crank tension lever 76 mounted for rocking movement on a rock shaft fulcrum 77 and having a relatively long tension or firing arm 78 and a relatively short actuating arm 80. The free end of the arm 78 seats between two lugs 81 and 82 fixed to the carry rack 56 and so spaced as to allow sufficient clearance for the arm 78 to shift from the addition tension position to the subtraction tension position when the carry rack 56 is locked in its normal position. The arm 80 terminates in a hook 83 which receives one end of a tension spring 84, the other end of which is held by a lug 85 formed on a carry tension bar 86. This bar 86 extends transversely of the machine and is supported at its ends by pivot pins 87, which are rotatably mounted respectively in parts of the frame 88. The pins 87 are respectively fixed to crank arms 90, which serve to space the tension bar 86 at the proper distance from its axis of rotation and also to support the same therebetween. In this connection it should be noted that the axis of rotation of this tension bar 86 is coincident with or passes through the point of attachment of the spring 84 with the hook 83, so that when the bar 86 swings from an adding position to a subtracting position there is no appreciable variation in the tension of the spring. The distance between the hook 83 and the lug 85 is such as to 100 place a tension upon the spring sufficient to effectively fire the carry rack 56 when the latter is released to be subjected to the action of the operating arm 78. This arrangement, while supplying the desired spring firing action to the carry racks, permits a minimum tension to be used, and through the coincident axes of the spring and carry tension bar 86, there is no added spring tension transmitted to the operating levers during the setting of these parts. It will be noted in Fig. 5 that the above described construction insures an operating arm 78 having the necessary tension to kick the carry rack in one direction if set for adding and in the opposite direction if set for subtracting, this being due to the shifting of the direction of the pull of the spring 84 upon the tension lever hook arm 80 and because the fulcrum 77 of the arm 78 is between the attachment point of the spring and the carry rack end of the arm 78.
- For automatically shifting the carry tension bar 86 when a change is to be made from one form of calculation to the other,

the respective crank arms 90 are provided with laterally extending pins 91, which seat respectively in end slots 92 of the levers 93, and are oscillated as the levers 93 are rocked by movement of the shaft 77 under the action of a link 94 which is fast to the shaft 77. This link 94 has a pin 95 seated in a bifurcated extension 96 at one side of a slide plate 97. That is to say, at one side of the machine there is a slidably mounted plate 97 having a bifurcated extension 96 which straddles a pin 95 on a link 94, so that when the plate is shifted in the cycle of operations it will cause the link 94 to rock the shaft 77 and thereby transmit motion to the levers 93 so that the carry tension bar 86 with its associated parts is shifted from one position to another. In order to actuate the sliding plate 97 at the proper time to set the mechanism which it controls, it is supported in position upon the machine frame by stud bolts 98, which traverse respectively slots 100 in the aforesaid plate and permit the latter to have the required stroke in either direction. Motion is transmitted to the plate 97 by means of two trips 101 and 102, both being pivoted to the plate and arranged to be shifted from one position to another in accordance with whether or not the machine is to operate for an adding operation or for a subtracting operation. In the present instance the two trips 101 and 102 are connected by a tension spring 103 acting to rock the trips inwardly out of their functioning position. The trip 101 is arranged to control movement of the plate 97 for an adding operation while the trip 102 is similarly arranged to control movement of the plate 97 for a subtracting operation, and selection of one trip or the other is made by a selecting lever 104 having two oppositely disposed arms 105 and 106, one of which is arranged to engage a pin 107 on the trip 101 and the other arm 106 being arranged to engage a pin 108 on the trip 102. This lever 104 is pivoted at 109 to a fixed part and is connected at 110 to a link 111 which is connected by a crank 112 on a transverse shaft 113 running to the opposite side of the machine where a crank 114 connects by a link 115 with the selecting index arm 48. This selecting lever 104 is shown in position to release the subtraction trip 102 and the latter has therefore been thrown to operative position by the action of the spring 103, so that its lower extremity is in the path of movement of a trip pin 116 operatively located upon a rock cam 117. This cam 117 also carries a second trip pin 118, which is arranged to travel in the path of the addition trip 101, so that when the latter is released to operative position by a change in the setting of the selecting lever 104, this pin 118 will engage its trip 101 and cause the plate 97 to be shifted to a new position. The rock cam 117 is fixed

to the main shaft 16 and receives its motion in the cycle of operations during the operation of the main control arm or lever 13.

The operation of the machine is as follows:

For adding, the index lever 48 is swung counter-clockwise from the position shown in Fig. 2, to a position where the locking pin 50 is seated in the recess 53 and locked by the spring controlled latch 51. This movement of the index lever 48 is transmitted directly to the subtraction arm 46 and the addition arm 47, and indirectly, through the link 115, crank 114, shaft 113, crank 112, link 111, to the selecting lever 104. The action of the selecting rock bar 44 and the selecting lever 104 is the same and is carried out in unison; thus the subtracting arm 46 engages the pin 38 so that its continued movement swings the trip 36 about its pivot 37 out of the path of the trip pin 43, while the addition arm 47 moves away from the pin 34 and allows the trip 32 to be swung by the spring 41 into the path of the trip pin 42. Simultaneously on the opposite side of the machine the selecting lever 104 brings its arm 106 into engagement with the pin 108 to turn the trip 102 out of the path of the trip pin 116 and release the trip 101 so that it will be engaged by the trip pin 118 on the return stroke of the operating arm of the machine. With the setting of the machine for adding, the operator then punches the keys for the numbers to be added and follows this by pulling the main operating arm 13 forwardly. In consequence, the cam 15 is rocked in the same direction, its trip 43 passing the trip 36 and its trip pin 42 swinging the trip 32 out of the way to take a position to the left of trip 32 at the end of the forward stroke of the main arm 13. The same operation is taking place at the opposite side of the machine because the main shaft 16 transmits motion to the cam 117 and causes the trip pin 118 to take a position to the right of the trip 101. Upon the return stroke of the main arm 13 the respective pins 42 and 118 engage the addition trips 32 and 101 and since these trips are prevented from turning by reason of their pins 34 and 107 respectively abutting the edges of the cam slide 22 and the plate 97, the return rocking movement of the cam 117 causes the slide 22 and the plate 97 to move in the required direction. The movement of the cam slide 22 is simultaneously transmitted to the cam slide 23 so that these two slides 22 and 23 operate together and cause the pinion shaft 17 to ride down the right hand face of the cam 21 to bring the pinions 11 into mesh with the index racks 12 to roll in an adding accumulation at the proper time in the return stroke of lever 13. The movement of the slide plate 97 is transmitted by the bifurcated extension 96 to the pin 95 on the

- link 94 so that the latter is rocked to transmit this motion to the rock shaft 77 which through the levers 93 swings the carry tension bar 86 to the adding position. This shifting of the bar 86 changes the direction of pull of the carry tension spring 84 and consequently transfers the pressure of the firing arm 78 from the lug 81 to the lug 82 so that when the carry rack 56 is released it will be fired in the required direction to perform a carry operation. The foregoing adding operation takes place on the return stroke of the main lever 13, during the first part of which the pinions 11 roll in an adding accumulation and tripping such carry racks, as are to be set, by a fractional amount and before the return stroke is completed the resetting mechanism for controlling the carry racks is released and the firing arm 78 fires the set carry racks to allow full carry to take place. When this happens, the cam slides 22 and 23 have been returned to their normal position with the cams 21 raising the pinions 11 out of mesh with the index racks 12 and 25 in mesh with the teeth 60 of the carry racks 56 so that the motion of the fired carry racks turns the accumulator pinions a distance equal to one tooth and thus brings the next succeeding number of the required accumulation wheel into indicating position. In this connection it should be noted that it is impossible for the firing movement of the carry rack to overthrow because it has a positive lock stop through engagement with the carry pawl tab 63. This prevents a carry of more than one unit at each carry operation.
- For subtraction, the index lever 48 is swung clockwise to the position shown in Fig. 2, where the pin 50 is seated in the recess 55 and locked by the spring control latch 51. This movement of the index lever 48 is transmitted directly to the arms 46 and 47, and indirectly, by way of link 115 and shaft 113 to the link 111 of the selecting lever 104. The resulting movement of the lever 48 is to cause the addition trip 32 to be raised and held out of the path of the pin 42 on the return stroke of the latter, and to drop the trip 36 into the path of the pin 43 on the forward stroke of the latter. Therefore, as the cam 15 moves counter-clockwise on the forward stroke of the main operating lever 13, the pin 43 will engage the trip 36 and transmit motion to the connected cam slides 22 and 23 to cause them to move in the opposite direction to which they did on the addition operation. By reference to Fig. 1, it will be seen by this operation that the cam 60 slide 23 moves downwardly to the right, and thus allows the accumulator shaft 17 to ride down the upper side of the cams 21 so that the index racks 12 engage the pinions 11 to roll in a subtracting operation on the forward stroke.
- Following this rolling out of the subtraction operation the continued forward pull of the main operating lever 13 will cause the cam 117 to reach the position where the pin 116 engages the trip 102 and therefore transmits its motion to the slide plate 97 and move the latter downwardly to the right, as shown in Fig. 1, thus actuating the carry tension mechanism, including the pin 95, link 94, rock shaft 77, so that the carry tension bar 86 is swung counter-clockwise to subtraction position. During this swinging of the tension bar 86 the direction of pull of the tension spring 84 will be changed and result in shifting the firing arm 78 away from lug 82 and into engagement with lug 81, and places the carry racks under tension to carry in the opposite direction from which it bid for the addition carry. On the return stroke of the main lever 13 the cam slides 22 and 23 are automatically returned to their normal position, and consequently the pinion shaft 17 rides back to the top of the cams 21 and brings the aforesaid pinions again into mesh with the carry racks 56. When the main operating lever 13 has reached a point just before the end of its return stroke, the carry racks which have their control latches set for a carrying operation are released by a fractional amount, which insures the latches against return to the locking notches prior to the carry operation, and a continuation of the return movement finally releases the resetting mechanism controlling these carry racks so that the said racks are free to be fired by the tension or firing arms 78. These, of course, for the subtraction, are fired in the opposite direction from which they were during the adding carry operation. It will be noted that upon this return stroke of the operating lever 13 the cams 15 and 117 carry their pins 42 and 118 respectively past the addition trips 32 and 101, because these latter are held out of the way through the positioning of the selecting arms 44 and 104. Thus, for a subtracting operation, cam pins 43 and 116 are the ones functioning to shift the respective parts controlled thereby, while upon an adding operation the pins 42 and 118 become the operating pins for moving the respective parts in the opposite direction.
- It will now be apparent that a complete unitary carry tension mechanism for carry racks of adding and subtracting machines has been devised, wherein the heretofore complex mechanism for this purpose has been greatly simplified and the number of parts very materially reduced. This simplification of the carry tension mechanism results also in raising the percentage of durability and certainty of operation, as compared to carry tension mechanisms heretofore used which employ a multiplicity of 120 125 130

parts, including pawls, springs, detents, and the like. In the present invention all such trains of mechanisms have been eliminated with the result that defects due to the presence of the elements of such mechanisms are done away with. It should also be noted that the simplified carry tension mechanism of the present invention is common to both addition and subtraction carry operations and has therefore disposed of all parts which have been commonly brought into use for a subtraction carry in place of other parts employed during addition carry. Thus the present invention does away with expensive, complicated and burdensome parts which have been in long use and which the industry to which this invention pertains has found heretofore no method of dispensing with.

20 Although but one form is shown in which this invention may be embodied, it is to be understood that the invention is not limited to any specific construction, but might be applied in various forms without departing 25 from the spirit of the invention or the scope of the appended claims.

Having thus described my invention, I claim:

1. A mechanism for adding and subtracting machines comprising a reciprocal carry rack, an accumulator wheel arranged to be moved to mesh with said rack, a tension spring, a firing member connected to one end of said spring and arranged to hold said carry rack under tension, a fulcrum for said member located between said spring connection and the carry rack end of said member, and means connected to the other end of said spring for changing the direction 40 of the applied tension of said spring whereby the direction of carry of said carry rack can be reversed.

2. A mechanism for adding and subtracting machines comprising a reciprocal carry rack, an accumulator wheel arranged to be moved to mesh with said rack, a tension spring, a firing member connected to one end of said spring and arranged to hold said carry rack under firing tension, a fulcrum for said member located between said spring connection and the rack end of said firing member, and means including a pivoted arm connected to the other end of said spring for changing the direction of the applied tension 55 of said spring whereby the firing direction of said member is reversed to change from one form of carry to the other.

3. A mechanism for adding and subtracting machines comprising a reciprocal carry rack, an accumulator wheel arranged to be moved to mesh with said rack, a tension spring, a firing member connected to one end of said spring and arranged to hold said carry rack under firing tension, a fulcrum 60 for said member located between said spring

connection and the rack end of said firing member, and means including an arm pivoted on an axis coincident with the member end of said spring for changing the direction of the applied tension of said spring, 70 whereby the firing direction of said member is reversed to change from one form of carry to the other.

4. A carry tension mechanism for adding and subtracting machines comprising a 75 carry rack mounted to move in a direction for addition carry and in a direction for subtraction carry, a firing member arranged to cooperate with said carry rack, a tension spring connected to said member, means 80 holding said spring under constant tension, means for swinging said spring and holding means about the spring connection with said member as an axis to change the direction of the applied tension, a selecting device for 85 setting said swinging means for a predetermined carry operation, means actuated at a predetermined time in the operation of said machine for causing said swinging means to function, and means for locking 90 said selecting device in set position to retain said tension spring in the same position during all the selected operation.

5. A carry tension mechanism for adding and subtracting machines comprising a 95 carry rack mounted to move in a direction for addition carry and in a direction for subtraction carry, a firing member arranged to cooperate with said carry rack, a tension spring connected to said member, means 100 holding said spring under constant tension, means for swinging said spring and holding means about the spring connection with said member as an axis to change the direction of the applied tension, a selecting device for 105 setting said swinging means for an addition carry, and means actuated at a predetermined time in the addition stroke of said machine for causing said swinging means to function to shift said spring and holding 110 means from subtracting carry position to adding carry position.

6. A carry tension mechanism for adding and subtracting machines comprising a 115 carry rack mounted to move in a direction for addition carry and in a direction for subtraction carry, a firing member arranged to cooperate with said carry rack, a tension spring connected to said member, means holding said spring under constant tension, 120 means for swinging said spring and holding means about the spring connection with said member as an axis to change the direction of the applied tension, a selecting device for setting said swinging means for an addition carry, means actuated at a predetermined time in the addition stroke of said machine for causing said swinging means to function to shift said spring and holding means from subtracting carry position to adding carry 125 130

position, and means for locking said tension spring means for all successive addition operations.

7. In an adding and subtracting machine, 5 the combination of accumulator wheels, a common mechanism for controlling addition and subtraction, a carry rack, a latch arranged to lock said carry rack in a central position, means to automatically release said latch, a pivoted carry tension means for firing said carry rack, means to initially release said carry rack to set said carry rack for a 10 carry operation, means operating at the same side of the fulcrum of said carry tension for reversing the action of said carry tension upon said carry rack, and means for 15 fully releasing said carry rack to the action of said tension means.

8. In an adding and subtracting machine, 20 the combination of accumulator wheels, a

common mechanism for controlling addition and subtraction, a carry rack, a latch arranged to lock said carry rack in a central position, means to automatically release said latch, a pivoted carry tension means for 25 firing said carry rack, means to initially release said carry rack to set said carry rack for a carry operation, means operating at the same side of the fulcrum of said carry tension for reversing the action of said carry tension upon said carry rack, and means for 30 maintaining a substantially constant tension on said carry tension means when shifting said tension means from one form of carry to the other. 35

Signed at Philadelphia, county of Philadelphia, State of Pennsylvania, this 18th day of March, 1924.

WILLIAM W. LASKER.
